UNITED STATES PATENT OFFICE

2,063,031

HEATING APPARATUS

Benjamin W. Davis, Chicago, Ill.

Application December 14, 1934, Serial No. 757,533

2 Claims. (Cl. 126—99)

The present invention relates to an improvement in heating apparatus for buildings and like structures and for all other purposes, and has for an object to provide an improved apparatus which is adapted for use in heat exchange from all products of combustion.

One purpose of the present invention is to provide an apparatus wherein the medium of heat exchange is broken up into separate and independent streams and independently heated from different successive portions of the source of heat supply and wherein the surface area of contact between the heat exchange mediums is materially increased and segregated to effect the practically complete and thorough interchange of heat between the mediums.

Another object of the invention is to provide an apparatus wherein at all times the coldest stream of air or other medium is brought into contact with the successive zones of the heat emanating medium so as to insure the complete interchange of the heat between the mediums and to complete the wide-spread distribution of the same.

A further object of the invention is to provide a heating apparatus which may be operated with great economy in that a relatively high percentage of heat exchange is accomplished so that there will be practically but little waste heat carried off in the smoke and gases through the chimney, or otherwise.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a transverse section taken through a heating apparatus installed in an enclosure and embodying the features of the present invention.

Figure 2 is a transverse section taken through the same on the line 2—2 in Figure 1.

Referring now to the drawing and to the embodiment shown in Figures 1 and 2, 25 designates a heater of any suitable type and may be a coal, gas, or oil burner or constructed for use with any suitable source of heat energy. The heater 25 is provided with a flue or pipe 26 which, as shown in Figure 2, rises from one end portion of the heater and which, a short distance above the heater, is carried substantially horizontally but with a slight incline backwardly over the major portion of the heater to form a heating leg 27. This heating leg 27 is laterally enlarged to

substantially twice its diameter or enlarged to any extent desired with the transverse axis of the leg 27 inclined at an angle which may be of 40° or of any degree desired with respect to the horizontal so as to provide an extensive inclined surface area over which air or other suitable heat transferring medium may pass about the upper and lower sides and about the ends of the leg 27. The upper end of the leg 27 is turned upwardly and then returned in spaced relation to the leg to provide a second spaced leg 28 which is of similar construction and which may be disposed at a desired angle with respect to the heater and the leg 27. This leg 28 is off-set laterally with respect to the leg 27 so that the leg 28 will receive thereagainst and thereabout a stream of air which is laterally disposed with respect to the stream of air coming in contact with the leg 27, and any desired number of these legs 27 and 28 may be employed, according to the size of the heating apparatus and other conditions met with and these legs are all not only vertically spaced apart but also laterally off-set to provide successive zones of contact of the heating medium such as smoke and other products of combustion passing through the flue 26, into different streams or portions of the cold air which is admitted to the apparatus. The uppermost leg 29 is connected to a chimney 30 through which the products of combustion are carried out of the building after substantially all of the useful heat has been extracted therefrom.

In order to promote circulation of air upwardly about the heater and its heat emanating legs 27, 28 and 29, a casing 31 may be placed about these parts and may be of any suitable configuration and of any suitable height but as shown in the present instance as having one wall 32 curved upwardly and inwardly toward the opposite wall to form a contracted mouth or outlet for the heated air or other medium for passage into the room or enclosure.

The heating apparatus and the casing 31 are mounted upon a suitable flooring or base 34 and the casing 31 is provided in its straight wall or at any other suitable point with an air inlet opening 35 of suitable size and which is preferably closely adjacent the floor 34 so that the coldest air in the enclosure will be drawn into the casing. This opening 35 is preferably disposed opposite the wall 32 and the heater 25 is provided through its lower or base portion with two air passages 36 and 37 separated by a partition 38 which extends to the wall 32 for the purpose of completely segregating the passages 36 and 37. The pas-

sages 36 and 37 open at their inlet ends opposite the casing opening 35 so that the cold air entering the opening 35 may be divided into several cold air streams, including an upper relatively 5 clean air stream which enters the passage 36 above the partition 38 and is carried through the lower portion of the heater and freed between the heater and the wall 32. This upper stream of cold air is divided at the entrance to the passage 10 36 and passes in part upwardly about the adjacent side of the heater 25, and a baffle plate 39 may be placed in spaced relation about the adjacent side of the heater 25 and may extend upwardly into partly overlapping relation with 15 respect to the leg 27 so as to confine the cold air stream against the heater and also deflect it about the underside of the leg 27.

The baffle 39 may of course be disposed at any suitable angle and may be otherwise positioned 20 with respect to the leg 27 and as herein shown in order to deflect the cold air stream to the desired points of the apparatus.

The second cold air stream, adjacent the floor 34, is the dust-laden air stream and also contains 25 impure air and gases which gravitate to the floor and this second air stream is carried along the floor 34 through the passage 37 and through the wall 32 beneath the partition 38, an outlet pipe 40 being connected to the lower portion of the 30 wall 32 for carrying off this impure and dust-laden air directly to the chimney or stack 30.

As shown in Figures 1 and 2 this heating apparatus may be installed in a room having walls 41 and provided with a ceiling 42. The ceiling 42 35 may have a false ceiling 43 providing an air space 44 beneath the ceiling 42. The false ceiling 43 is provided with a desired number of openings 45 through which fresh air from outside the building, or other suitable source, may be admitted to the room or enclosure to displace the impure and dust-laden air which is extracted from the room or enclosure through the pipe 40 and stack 30. This serves as a ventilator and as a supply for fresh air to the room. This inflow 40 of fresh air thus properly conditions the air within the room. The opening 44 may be supplied with air through a suitable ventilator 46 or the like as shown.

The cold air entering the ventilator 46 passes

into the compartment or space 44 between the ceilings 42 and 43, and by virtue of the warm air in the room this fresh air is partially preheated to some extent before it is freed through the openings 45 into the room. It is of course understood that wherever it is required or found convenient clean-out doors, hand holes or other suitable devices or structures may be used for facilitating the cleaning out of the various flues and passages in the apparatus. 5 10

While I have herein shown and described a preferred form of my invention, it is nevertheless to be understood that various changes may be made in the details of construction, proportion and arrangement of parts within the scope of the 15 claims herewith appended.

What is claimed is:

1. Heating apparatus including a casing having an opening in the top and bottom thereof, one wall of the casing being inclined upwardly and 20 in the direction of the opposing wall, said opposing wall being substantially vertical and the bottom opening being in said vertical wall, a heater in the casing, a plurality of interconnected heat radiating flues connected at one end to the heater, 25 said flues being of flattened form with their longitudinal axes horizontal and with their flattened faces substantially parallel and inclined to the vertical in the direction of said one inclined wall, said flues being disposed in spaced apart stepped 30 relation in such a manner that the lower walls thereof form a heat exchanging baffle for the rising current of air.

2. Heating apparatus including a casing having an opening in the top thereof and an opening 35 adjacent the bottom of a vertical wall thereof, a heater in the casing, a plurality of interconnected heat radiating flues connected at one end to the heater, said flues being of flattened form with their longitudinal axes horizontal and with 40 their flattened faces substantially parallel and inclined to the vertical in the direction of the wall opposite from said one vertical wall, said flues being disposed in spaced apart stepped relation in such a manner that the lower walls thereof 45 form a heat exchanging baffle for the current of air rising substantially vertically from said bottom opening.

BENJAMIN W. DAVIS.
